DESIGN FOR A DRESS ENSEMBLE

Pauline Fracchia, New York, N. Y.

Application December 9, 1937, Serial No. 73,494

Term of patent 3½ years

To all whom it may concern:

Be it known that I, Pauline Fracchia, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a rear view of the dress unit shown in Figure 2.

Figure 4 is a rear view of the jacket unit of the dress ensemble.

The characteristic feature of my design resides in the combination on the ensemble disclosed of the specific dress section having a high V shaped yoke extending to the bustline, a seam terminating in a pleat depending from said yoke, in association with patch shirring on said yoke and a ruching bow, as shown.

I claim:

The ornamental design for a dress ensemble, substantially as shown and described.

PAULINE FRACCHIA.
